CONTROL DEVICE FOR CIRCUIT BREAKERS

Stanley T. Schofield, deceased, late of Wilkinsburg, Pa., by Martha M. Schofield, administratrix, Wilkinsburg, Pa., assignor to Westinghouse Electric & Manufacturing Company, East Pittsburgh, Pa., a corporation of Pennsylvania

Application December 31, 1936, Serial No. 118,577

18 Claims. (Cl. 200—106)

The invention relates to electric control devices in general and more particularly to electric control devices for tripping circuit breakers to open the contacts thereof.

- 5 In medium and high voltage alternating-current power distribution systems, the circuit breakers used are relatively large and considerable energy is required to move the relatively heavy latch means to trip the breakers. In 10 many instances, auxiliary sources of power are not available or practical and the practice has been to derive the energy for tripping the breaker from a current transformer associated with the circuit or line controlled by the breaker. One 15 type of arrangement has been the provision of an alternating-current electromagnet for tripping the latches of the breaker, the electromagnet being connected in a control circuit which is energized by a current transformer coupled 20 to the line controlled by the breaker. The inefficient use by the electromagnet of the limited power available makes this arrangement unsatisfactory particularly in view of the use of larger and heavier circuit breakers.
- 25 It is accordingly an object of the invention to provide a novel trip device for tripping large circuit breakers, which device is operable by a low energy control circuit.

Another object of the invention is the provision 30 of an improved trip device for circuit breakers capable of tripping larger breakers with a lower energy control circuit than any trip devices heretofore known or used.

Another object of the invention is to provide 35 a novel low energy alternating-current trip device for a circuit breaker which is simple, reliable, and inexpensive to manufacture.

Another object of the invention is the provision 40 of a novel low energy alternating-current trip device for a circuit breaker, which embodies an adjustable means for varying the time required for tripping the breaker.

The novel features that are considered characteristic of the invention are set forth in particular in the appended claims. The invention itself, however, both as to structure and operation, together with additional objects and advantages thereof, will best be understood from the following detailed description of an embodiment 50 of the invention when read in connection with the accompanying drawing, in which:

The single, partly diagrammatic, figure shows the trip device embodying the features of invention, in side elevation; the circuit breaker 55 being shown in diagrammatic form.

It will be understood that the trip device embodying the features of the invention is capable of application to substantially any type of circuit breaker and for this reason the circuit breaker with which the trip device is shown associated in the drawing has been illustrated in a diagrammatic manner.

Referring to the drawing, the circuit breaker, which is illustrated diagrammatically, comprises a pair of stationary contacts 3, a movable brush contact 5 connected to a pair of toggle links 7 and 9 which form a part of the operating mechanism for closing the circuit breaker, a releasable latch means 11 for restraining the movable brush contact 5 in closed circuit position, and a spring means 13 for biasing the movable brush contact 5 to the open circuit position. The latch member 11 is pivotally mounted by means of a pivot pin 15 and is biased to latching position, as shown, by means of a weighted extension 17. 20

The trip device comprises in general a support 19, a trip lever 21, a latch 23, a vibratory energy storing device indicated generally at 25, an electromagnet 27 for the vibrating device to store energy therein, and a control circuit 29 for energizing the electromagnet. 25

The trip lever 21 is pivotally mounted on a bracket 31 by means of a pivot pin 33. One end of the trip lever 21 carries a trip projection which, in the form shown, comprises a screw 35 which is threaded through the trip lever adjacent its left-hand end. A lock nut 37 is provided for locking the screw 35 in adjusted position. The opposite end of the trip lever carries the pivoted latch member 23. The latch member 23 has a 30 depending hook-shaped latch portion 39 and a weighted extension 41. The latch member 23 is pivotally mounted on the right-hand end of the trip lever by means of a pivot pin 43 and is biased in a clockwise direction about the pivot pin 43 35 by means of the weighted extension 41. A stop pin 45 is mounted on the trip lever 21 for limiting clockwise rotation of the latch member 23. 40

The vibratory energy storing device comprises a spring 47 and a weight member 49. One end 45 of the spring 47 is bent over and secured to the support 19 by means of a holding screw 51. The weight member 49 is secured to the opposite or free end of the spring 47 in any suitable manner. The upper end of the weight member 49 is provided with a latch engaging projection 53 which is adapted to be latched into engagement with the hook-shaped end 39 of the latch member 23 50 when the weight member attains a predetermined amplitude of vibration. 55

The alternating-current electromagnet 27 is mounted adjacent the central portion of the spring 47 by means of an angle-shaped bracket 55. The vertical leg of the bracket is provided with an adjusting slot 57, and is secured to the support 19 by means of a bolt 59 and a nut 61. The body portion of the bolt 59 passes through an opening in the support 15, through the slot 57 of the bracket 55, and a lock washer 63 is positioned between the vertical leg of the bracket 55 and the nut 61. This arrangement provides an adjustable mounting means for the electromagnet 27, whereby the air gap between the core of the electromagnet and the spring 47 may be adjusted in order to vary the time required for the weight member to attain a predetermined amplitude of vibration. The electromagnet 27 is connected in a control circuit 29 which, in the embodiment shown, receives its energy from a current transformer 65 which is coupled to the line L1 controlled by the breaker. A control switch 67 is interposed in the circuit 29 for controlling energization of the electromagnet 27.

The spring 47 is composed of magnetic material so as to be influenced by the pull of the electromagnet. If desired, the spring 47 may be provided with an armature 69 secured to the spring at a point above the core of the electromagnet 27. The spring 47 and the weight member 49 are so proportioned that the natural or inherent frequency of vibration of these connected members corresponds to the frequency of the alternating pull of the electromagnet 27 or to the frequency of the control circuit 29 so that when the control circuit is closed by the switch 67, the electromagnet causes the spring 47 and the connected weight member 49 to vibrate with increasing amplitude to store energy in said weight.

The operation of the device is as follows: With the parts in the position shown in the drawing, let it be assumed that it is desired to trip the breaker. Control switch 67 is closed either manually or by means of a relay to effect energization of the electromagnet 27 by means of the control circuit 29. The energization of the electromagnet 27 causes the spring 47 and connected weight member 49 to vibrate with increasing amplitude. After a predetermined time, the amplitude of vibration of the spring 47 and connected weight member 49 is increased to such an extent that the upper end of the weight member 49 engages the weighted extension 41 of the latch 23 to effect partial counter-clockwise rotation of the latch. The partial counter-clockwise rotation of the latch 23 causes the hook-shaped latch portion 39 to engage under the latch projection 53 of the weight member 49. The downward movement of the weight member, in which considerable energy has been stored, effects clockwise rotation of the trip lever 21 about its pivot pin 33 and causes the screw 35 to engage and move latch means 11 in a clockwise direction to effect release of the toggle linkage 7-9. The release of the toggle linkage 7-9 permits the biasing spring means 13 to move the toggle links to collapsed position which effects movement of the movable brush contact 5 to its open circuit position.

At a predetermined point in the downward movement of the weight member 49, the latch 23 releases the trip lever 21 from its connection with the weight member 49. The trip lever 21 is returned to the normal position shown by the return movement of the biased latch means 11 to

its latching position. The control circuit 29 is deenergized by the opening of the movable contact 5. The parts of the trip device are thus restored to their normal position ready for a subsequent operation. The circuit breaker is closed by the operating mechanism (not shown), and the latch means 11 reengages the toggle linkage 7-9 to latch the breaker in closed circuit position.

It will thus be seen that even though the power available in the control circuit 29 is low, the improved trip device provides an arrangement for tripping extremely heavy breakers by the energy derived from the low power control circuit. This is rendered possible by reason of the fact that the energy derived from the control circuit is stored in the vibratory device comprising the spring 47 and the weight member 49, over a period of time. Thus enough energy can be stored in the weight member 49 to trip large heavy breakers.

The trip device described may also be utilized as a time delay overload trip device by providing a means for closing the switch 67 in response to overload conditions in any well known manner. In such case, the time delay between the energization of the control circuit 29 and the tripping of the breaker can be varied by adjusting the position of the electromagnet 27 by means of the slot 57, the bolt 59, and the nut 61; to vary the air gap between the core of the electromagnet and the spring 47. By increasing the air gap, the weight member 49 will be influenced less by the electromagnet and thus require a longer time to build up to the required amplitude of vibration to trip the breaker.

The trip device may also be used as an over-voltage or under-voltage trip means by making the control switch 67 responsive to over-voltage or under-voltage conditions.

It is obvious that the trip device described is applicable to various types of circuit breakers. For example, in the case of a three-pole circuit breaker, the trip lever 21 would be arranged to engage and move the trip bar of the breaker to tripping position when the weight member 49 attains a predetermined amplitude of vibration. Likewise, the trip device is applicable to other forms of circuit breakers involving different types of latch means and operating mechanisms.

It will thus be seen that the invention provides a novel and improved trip device for circuit breakers which is simpler, more reliable, and less expensive to manufacture than trip devices that have heretofore been known or used. The invention also provides an alternating-current trip device for circuit breakers which is capable of tripping larger breakers with a lower energy control circuit than has heretofore been considered possible.

While the invention has been disclosed in accordance with the provisions of the patent statutes, it is to be understood that various changes in details of structure may be made without departing from the spirit of the invention. It is desired, therefore, that the invention be limited only by the reasonable construction of the appended claims, and by the prior art.

The invention claimed is as follows:

1. In a circuit breaker having relatively movable contacts biased to open circuit position and means for releasably holding said contacts in closed circuit position, the combination of a trip device comprising a vibratory mass, electromagnetic means for vibrating said mass with increas-

40

75

ing amplitude, said mass being operable upon the attainment of a predetermined amplitude of vibration to effect release of said holding means to permit opening of said contacts.

5. 2. In a control device, the combination of a vibratory member, an electromagnetic means for vibrating said member with increasing amplitude and means operated by said member when it attains a predetermined amplitude of vibration for effecting actuation of said control device.

10. 3. In a circuit breaker having relatively movable contacts, means biasing said contacts to open circuit position, releasable latch means for holding said contacts closed, a trip device comprising a vibratory member, an electromagnetic means for vibrating said member with increasing amplitude, said member being operable upon the attainment of a predetermined amplitude of vibration to release said latch means to allow 15 said contacts to be opened by said biasing means.

15. 4. In a control device, a vibratory mass, an alternating-current electromagnet for vibrating said mass, a low energy alternating-current control circuit for said electromagnet, the energization 20 of said circuit causing said electromagnet to vibrate said mass with increasing amplitude, said mass being operable upon the attainment of a predetermined amplitude of vibration to effect operation of said device.

25. 5. In a circuit breaker having relatively movable contacts biased to open circuit position, releasable means for holding said contacts closed, an energy storing device, means including an electromagnet and a low energy control circuit 30 for storing energy in said device at a certain rate, said device being operable upon the attainment of a predetermined amount of energy to effect release of said holding means to permit said contacts to open.

35. 6. In a circuit controlling device, the combination of a spring suspended vibratory mass, an alternating-current electromagnet, a low energy alternating control circuit for energizing said electromagnet, said spring suspended mass having 40 a natural frequency of vibration corresponding to the frequency of the alternating pull of said electromagnet so that said spring suspended mass is vibrated with increasing amplitude by said electromagnet, and means operable by said mass when it attains a predetermined amplitude of vibration for effecting operation of said device.

45. 7. In a circuit breaker, relatively movable contacts, means biasing said contacts to open circuit position, releasable means for holding said contacts closed, a trip device comprising an energy storing vibratory member, an alternating-current electromagnet for vibrating said member to store energy therein, a low energy control circuit for energizing said electromagnet, the natural 50 frequency of vibration of said member corresponding to the alternating pull of said electromagnet so that said member is vibrated with increasing amplitude as energy is stored therein, means operable by said member when a predetermined amount of energy is stored therein to release said holding means to permit said contacts to open.

55. 8. In combination, a circuit controlling device, a spring secured to a support at one end, a weight 55 secured to the free end of said spring, an alternating-current electromagnet mounted adjacent said spring for vibrating the same when said electromagnet is energized, a low energy alternating-current control circuit for energizing said electromagnet, the natural frequency of vibration 60

65. 9. In a circuit breaker, relatively movable contacts biased to open circuit position, a releasable latch means for holding said contacts closed, a trip device comprising a vibratory member, an alternating-current electromagnet for vibrating said member, a low energy control circuit for energizing said electromagnet, the proportions 70 of said member being such that its natural frequency of vibration corresponds to the frequency of pull of said electromagnet so that the amplitude of vibration of said member increases at a certain rate, means operable by said member when it attains a predetermined amplitude of vibration for moving said latch means to cause said contacts to open.

75. 10. A circuit controlling device, control means for said device comprising a vibratory member, an alternating-current electromagnet for vibrating said member, a low energy control circuit for energizing said electromagnet, the proportions of said member being such that its natural frequency of vibration corresponds to the frequency of pull of said electromagnet so that the amplitude of vibration of said member increases at a certain rate, means operable by said member when it attains a predetermined amplitude of vibration for effecting operation of said device, and means for varying the rate of increase of amplitude of vibration of said member to vary the time required for said member to effect operation of said device.

80. 11. In a control device, means for actuating said device comprising a vibratory member, an alternating-current electromagnet for vibrating said member, a low energy control circuit for energizing said electromagnet, said electromagnet when energized causing said member to vibrate with increasing amplitude, said member when it attains a predetermined amplitude of vibration effecting actuation of said device, and means for varying the time required for said member to attain said predetermined amplitude.

85. 12. In a circuit breaker, stationary contact means, a switch member movable to open or to closed circuit position to open or to close the circuit, means biasing said switch member to open circuit position, releasable latch means for holding said switch member in closed circuit position, a trip device for releasing said latch means comprising a vibratory spring supported weight means, said weight means being operable upon the attainment of a predetermined amplitude of vibration to release said latch means to allow said switch member to move to open circuit position, an alternating-current electromagnet for vibrating said weight means to store energy therein, and a low energy alternating-current control circuit for energizing said electromagnet, the natural frequency of vibration of said spring supported weight means corresponding to the frequency of said control circuit so that said weight means is vibrated with increasing amplitude during energization of said circuit.

90. 13. In a circuit breaker, stationary contact means, a switch member movable to open or to closed circuit position to open or to close the circuit, means biasing said switch member to open

- circuit position, releasable latch means for holding said switch member in closed circuit position, a trip device for releasing said latch means comprising a vibratory spring supported weight means, said weight means being operable upon the attainment of a predetermined amplitude of vibration to release said latch means to allow said switch member to move to open circuit position, an alternating-current electromagnet for 10 vibrating said weight means, a low energy alternating-current control circuit for energizing said electromagnet, the natural frequency of vibration of said spring supported weight means corresponding to the frequency of said control circuit so that said weight means is vibrated with increasing amplitude during energization of said circuit, and means for varying the time required for said weight means to attain said predetermined amplitude.
14. In a circuit controlling device, means for actuating said device, comprising a vibratory spring supported weight means, said weight means being operable upon the attainment of a predetermined amplitude of vibration to effect actuation of said device, an alternating-current electromagnet for vibrating said weight means, a low energy alternating-current control circuit for energizing said electromagnet, the natural frequency of vibration of said spring supported weight means corresponding to the frequency of said control circuit so that said weight means is vibrated with increasing amplitude during energization of said circuit, and means for adjusting the position of said electromagnet to vary the time required for said weight means to attain said predetermined amplitude.
15. In a circuit breaker, relatively movable contacts, means biasing said contacts to open circuit position, releasable latch means for holding said contacts closed, a trip device comprising a spring secured to a support at one end, a weight secured to the free end of said spring, an alternating-current electromagnet mounted adjacent said spring for vibrating the same when said electromagnet is energized, a low energy alternating-current control circuit for energizing said electromagnet, the natural frequency of vibration of said spring and connected weight corresponding to the frequency of the control circuit so that said spring and weight are vibrated with increasing amplitude during energization of said circuit, means operable by said weight when said spring and weight attain a predetermined amplitude of vibration for effecting release of said latch means to allow said biasing means to open said contacts, and means for varying the time re-
- quired for said spring and weight to attain said predetermined amplitude of vibration.
16. In a circuit controlling device, means for actuating said device comprising a spring secured to a support at one end, a weight secured to the free end of said spring, an alternating-current electromagnet mounted adjacent said spring for vibrating the same when said electromagnet is energized, a low energy alternating-current control circuit for energizing said electromagnet, the natural frequency of vibration of said spring and connected weight corresponding to the frequency of the control circuit so that said spring and weight are vibrated with increasing amplitude during energization of said circuit, said weight and spring upon the attainment of a predetermined amplitude of vibration effecting actuation of said device, and means for adjusting the position of said electromagnet relative to said spring for varying the time required for said spring and weight to attain said predetermined amplitude of vibration.
17. In a circuit breaker, relatively movable contacts, means biasing said contacts to open circuit position, releasable means for holding said contacts closed, a trip device comprising an energy storing vibratory member, an alternating-current electromagnet for vibrating said member to store energy therein, a low energy control circuit for energizing said electromagnet, the natural frequency of vibration of said member corresponding to the alternating pull of said electromagnet so that said member is vibrated with increasing amplitude as energy is stored therein, means operable by said member when a predetermined amount of energy is stored therein to release said holding means to permit said contacts to open, and means for varying the time required for said vibratory member to effect release of said holding means.
18. In a circuit breaker having relatively movable contacts biased to open circuit position, releasable means for holding said contacts closed, an energy storing device, means including an electromagnet and a low energy control circuit for storing energy in said device at a certain rate, said device being operable upon the attainment of a predetermined amount of energy to effect release of said holding means to permit said contacts to open, and means for varying the time interval between energization of said circuit and the release of said holding means.
